GAME LAYOUT CHART

William N. Mitchell, P.O. Box 1183,
Visalia, Calif. 93277

Filed July 10, 1968, Ser. No. 12,677

Term of patent 14 years

Int. Cl. D21—01

U.S. Cl. D34—5

The figure is a top plan view of a game layout chart showing my new design.

The chart has no appreciable thickness and the under-surface thereof is plain and unornamental.

I claim:

The ornamental design for a game layout chart, as shown and described.
